UNITED STATES PATENT OFFICE

168,863

CONDIMENT HOLDER

William Dow Scalf, Barbourville, Ky.

Application May 24, 1950, Serial No. 10,133

Term of patent 3½ years

(Cl. D44—22)

To all whom it may concern:

Be it known that I, William Dow Scalf, a citizen of the United States of America, residing at Barbourville, in the county of Knox and State of Kentucky, have invented a new, original, and ornamental Design for a Condiment Holder, of which the following is a specification, a reference being had to the accompanying drawing, forming part thereof.

Fig. 1 is a front elevational view of a condiment holder, showing my new design;

Fig. 2 is a side elevational view;

Fig. 3 is a bottom plan view; and

Fig. 4 is a top plan view thereof.

I claim:

The ornamental design for a condiment holder, as shown.

WILLIAM DOW SCALF.
